UNITED STATES PATENT OFFICE.

ISAAC NEUMAN, OF PITTSBURG, PENNSYLVANIA, ASSIGNOR OF ONE-SIXTH TO FRANK MAGIDSON, ONE-SIXTH TO EDWARD ISAACSON, ONE-SIXTH TO HARRY A. LANDE, AND ONE-SIXTH TO PHILEP ADLER, ALL OF PITTSBURG, PENNSYLVANIA.

CHALK-SHARPENING DEVICE.

947,186.

Specification of Letters Patent. Patented Jan. 18, 1910.

Application filed January 9, 1909. Serial No. 471,483.

To all whom it may concern:

Be it known that I, ISAAC NEUMAN, a citizen of the United States of America, residing at Pittsburg, in the county of Allegheny and State of Pennsylvania, have invented certain new and useful Improvements in Chalk-Sharpening Devices, of which the following is a specification, reference being had therein to the accompanying drawing.

This invention relates to chalk sharpening devices, and the primary object of my invention is to provide simple and effective means for sharpening a piece of soapstone or chalk, without soiling the hands, and without wasting the chalk due to breakage when sharpening.

Another object of this invention is to provide a soapstone sharpener that can be advantageously used by tailors, and dressmakers, for providing a piece of soapstone or similar marking substance with a beveled marking edge.

A further object of the invention is to provide a soapstone sharpener in which the waste product is collected, and can be saved and used for other purposes.

A still further object of the invention is to provide a durable and compact device that can be easily operated without clogging.

With the above and other objects in view which will more readily appear as the invention is better understood, the same consists in the novel construction, combination and arrangement of parts to be described, and then claimed.

In the drawings, Figure 1 is a front elevation of the sharpening device, Fig. 2 is a side elevation of the same, Fig. 3 is a vertical longitudinal sectional view of the device partly in elevation, and Fig. 4 is a vertical cross sectional view of the device.

In the accompanying drawings, 1 designates a rectangular casing having end flanges 2, to permit of said casing being secured to a suitable support. The casing is provided with an open side 3 for a drawer 4 having a front plate 5 adapted to close upon the open side of the casing 1, said front plate 5 having a suitable knob or button 6 to permit of the drawer being easily removed.

The top of the casing 1 is provided with a longitudinal slot 7, and mounted upon said

casing is a cylindrical housing 8, disposed longitudinally, relative to the casing 1 and above the slot 7, said housing being secured to the casing 1, by bolts 9 and nuts 10. The rear wall of the housing 8 is provided with a central outwardly extending sleeve 11, and journaled in said sleeve is a shaft 12 having the inner end thereof provided with a rotary cutter, while the outer end of the shaft 12 is provided with a detachable crank 13. The rotary cutter comprises a disk provided with a hub 14 and having a plurality of tangentially disposed cutter blades or knives 15, said knives connected to one face thereof being triangular in cross section, with the side edges thereof converging toward the hub 14, the front and rear edges thereof in vertical parallel planes, and the arrangement of said knives providing spaces 16 for clearance of material cut from a piece of soapstone held in the path of the front edges of the knives. The knives or cutters extend from the hub 14 to the edge of the disk.

The housing 8 is provided with a detachable front plate 17 secured by bolts 18 and nuts 19 to a peripheral flange 20, carried by the housing 8. The upper edge of the flange 20 is cut away, as at 21, to accommodate a chute 22, in which a piece of soapstone, or chalk is placed to be held in position to be operated upon by the rotary cutter. The chute 22 is cut away, as at 23, and this cut away portion, in connection with the cut-away portion of the flange 20, permits of a piece of soapstone being manually held by one hand while the crank 13 is rotated with the other.

The soapstone or chalk removed by the knives 15, of the rotary cutter, passes between the plates to the rear side of the cutter and descends into the drawer 4. Since the rotary cutter extends into the slot 7 the soapstone or chalk carried by the knives will be eventually deposited into the drawer, but the manner in which the device is assembled, permits of the entire device being easily cleaned and the plates thereof sharpened.

The device is made of strong and durable metal, and while in the drawings forming a part of this application there are illustrated the preferred embodiments of my invention, I would have it understood that the details of construction can be varied or changed as

to the shape, proportion and manner of assemblage without departing from the spirit of the invention.

Having now described my invention, what 5 I claim as new, is:—

A chalk sharpening device comprising a casing, a drawer slidably mounted in said casing, said casing having its top provided with a longitudinally extending slot, a housing mounted upon said casing and opening into said slot, a sleeve projecting rearwardly from said housing, a shaft journaled in the sleeve and extending in the housing, a disk having a centrally disposed hub connected 10 to said shaft, tangentially disposed knives 15 to said shaft, tangentially disposed knives

connected with one face of said disk and extending from said hub to the edge of the disk, a crank connected to the shaft for rotating the disk and further adapted to prevent longitudinal movement of said shaft, 20 and an inclined chute connected with the top of the housing and adapted to position a piece of chalk engaged by said knives whereby the chalk is sharpened.

In testimony whereof I affix my signature 25 in the presence of two witnesses.

ISAAC NEUMAN.
